JERRY J. RACETTE, OF PORTLAND, OREGON

WINDOW-SHADE SUPPORT

Application filed July 22, 1930. Serial No. 469,694.

My invention relates to supports for window shades of the roller type and has for its object the supporting of the window shade and at the same time providing a compressible shock absorbing member to prevent the striking of the window sash with the shade support.

I am aware that heretofore roller blind supports have been constructed which may be mounted within the runway of the lower sash. But these supports have all proven objectionable when so positioned for the reason that no provision was made therein to prevent the lower sash, when being raised, from striking and breaking the shade supporting roller, or dislodging the support.

A further object of my device is to provide a broad resilient bumping surface extending the full width of the runway of the lower window sash which will not injure the edges of the lower sash, when the same is brought sharply in contact therewith. The supports which are being manufactured at the present time are constructed of thin metal, and all are objectionable for the reason that they break or split the edges of the sashes. My device also prevents the window lock which is usually fitted to the upper rail of the lower sash, from striking and tearing holes in the rolled shade.

A further object of my device is to provide a noiseless shock absorbing bumper, constructed of rubber, felt or other resilient material, and one that may be readily renewed without demounting the shade support.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a cross section of a window frame showing one of my new and improved window shade holders in place within the frame with the window shade roller shown removed.

Fig. 2 is a fragmentary front elevation par-

tially in section of a window frame showing one of my new and improved window shade supports in place within the frame and the roller in position.

Fig. 3 is a perspective view of one of my new and improved supports shown removed.

Fig. 4 is a perspective view of the shock absorbing element the object of which is to prevent the engagement of the window sash with that of the support.

Fig. 5 is a fragmentary front elevation in an enlarged view of a window frame illustrating one of my new and improved devices in place.

Like reference characters refer to like parts throughout the several views.

1 is the guideway disposed in a window frame and 2 and 3 are the guide strips disposed at either side of the guideway for maintaining the window sash 4 in position and alignment. The window shade support or plate is shown at 5 having a recess or angular slot 6 formed therein for the reception of the roller shade ends or support pins therein. 7 and 8 are openings for the fastenings for securing the holder or plate in position within the guideway of a window frame. The purpose of my new and improved support is two-fold. The primary object is to prevent the dislodgment of the window shade supporting member. The secondary object is to prevent the dislodgment of the roller itself.

An off-set 9 is provided in the supporting member and a surface 10 is formed at an angle to the off-set which is preferably parallel to the main body portion 5 of the device. The off-set should be formed at a lower point from the slot 6 than the greatest radius of the window shade when rolled up to permit free turning of the roller and shade when being wound to the full extent. A bumper 11, preferably of live rubber but may be felt or any resilient element, is disposed transversely of the guideway 1 and is of a thickness approximately that of the off-set 9 and extends below the lower edge of the length of the surface 10 so that as the sash 4 is raised sufficiently it will strike the bumper 11 directly and not the roller or shade nor the window shade support itself. The fastening passed through the

opening 8 are made to pass through the bumper as well and maintain the bumper and support in position.

This bumper is made to extend beyond the vertical edges of the plate, and in fact I find that the best results are obtained when the bumper extends the full width of the sash guideway, the purpose of this is twofold. First, it provides a greater shock absorbing surface. Second, to provide a shelf like portion at the top thereof. In some instances, when the lower sash is raised and sharply engages the bumper, the jar will cause the shade roller to become dislodged, and permit the same to fall with possible damage to the shade. This cannot happen when the bumper extends the full width of the runway, for the reason that the pins or shafts of the roller will strike the shelf like upper edge of the bumper or the off-set portion of the support, and the roller will be prevented from falling farther.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. In a device of the class described, the combination mountable within a sash runway of a window frame comprising a body member provided with an angular slot central thereof and openings adjacent each end for the passage of fastening means therethrough; an offset provided adjacent the lower end of the body member to space the lower end from the window frame; a rectangular resilient bumper member disposed within the space between the offset portion and the window frame, and means for maintaining said bumper within said space.
2. In a device of the class described, a plate provided with an angular slot at one edge and extending inwardly thereof; there being holes formed in said plate adjacent its ends for the passage therethrough of means to secure said plate to a vertical surface; said plate being formed with an off-set spaced from its lower end to form a lower portion spaced from said vertical surface; a rectangular resilient element positioned within said space; said resilient element projecting beyond the lower end and side edges of said plate, and having a hole therethrough registering with the hole formed in said plate adjacent its lower end; and securing means to pass through said holes to secure said plate and said resilient element to said vertical surface.

JERRY J. RACETTE.
